UNITED STATES PATENT OFFICE.

FRED M. YOUNG, OF RACINE, WISCONSIN, ASSIGNOR TO RACINE RADIATOR COMPANY,
OF RACINE, WISCONSIN, A CORPORATION OF WISCONSIN.

SHIPPING CRATE.

Application filed August 22, 1925. Serial No. 51,811.

This invention relates to means for protecting goods in storage and shipment, and more especially to shipping crates for internal combustion engine radiators, particular reference being had to radiators for automobile engines. Heretofore, owing to inadequate crate protection and packing, great loss and damage have resulted from injury to radiators of the character referred to above, incident to their transportation and general handling, often under conditions which are very severe on such goods.

The main object of this invention is to devise a convenient and inexpensive form of crate adapted for ready standardization to meet a wide range of needs and capable of thoroughly protecting the radiator against the rough handling which inevitably occurs incident to the commercial shipment and handling of such a product, which heretofore frequently resulted in wrenching the frame work, springing the joints and causing leaks, whereby replacement and return of the radiators to the factory has been necessary.

An illustrative embodiment of this invention is shown by the accompanying drawings, in which:—

Figure 1 is a perspective view of the crate alone in its partly open position and showing the back or lid side.

Fig. 2 is a longitudinal section on the line 2—2 of Fig. 4 through the center of the crate swung wide open, with a radiator and certain loose frame parts being lowered into place, the radiator and crate being shown face down.

Fig. 3 is a longitudinal, vertical section of the crate, on the line 2—2 of Fig. 4 with the radiator in position, with the lid closed and with the fastening wires twisted together, ready for shipment.

Fig. 4 is a top plan view of a crate with the back or lid part removed and showing the radiator in position.

Fig. 5 is a detail fragmentary view illustrating the tongue and groove joint construction of the crate frame.

In the construction shown by the drawings, the crate as a whole comprises four relatively loose or independent parts, namely an outside foldable wrapper 1, a pair of side blocks or filler members 2 and a centering plate 3, all adapted and arranged for

mutual assemblage and ultimate fastening 55 to secure the radiator 4 snugly in place.

The wrapper or main frame part 1 comprises four sections including a closed bottom member 5 to receive the face of the radiator, a base member 6, a top end member 7, and a top side or closure member 8, all foldably connected together as will be apparent from Figs. 1 and 2 and as will be explained, reinforcing and fastening means 9 being provided in the form of wires secured by staples 9', the ends of said wires being adapted and arranged for twisting together at 10 to lock the crate in its closed position.

The said wrapper sections 5 and 6 are 70 hinged together at 11, a similar joint 12 being provided for the members 5 and 7, and another hinge joint 13 being provided for connecting the lid or top side 8 to the end 7. The free end of lid 8 is provided with 75 corner tongues 14 to fit in the grooves 15 of end member 6, whereby a rigid joint is provided at this corner. The connection at this point is secured by the wires 9, twisted together as above stated, which fastening 80 may be supplemented if desired by a pin inserted at 15'. The said end member 6 comprises a pair of end corner bars 16 connected by a wall plate 17. The bottom member 5 comprises mainly a pair of side rails 18 and 85 substantially tight closure means or flooring 19. A spacer block 18' is secured permanently to the inner side of the rail 18 at the end adjacent to member 6, to center the base end of the radiator. The member 7 includes a pair of end corner bars 20, in combination with a connecting plate or board 21. The lid 8 comprises a pair of side rails 22, and spaced cross bars or slats 23.

The side block or filler members 2 are 95 adapted for inserting after the radiator has been set in place on the floor 19, and serve to secure the radiator rigidly and block movement thereof within the member 1, as will be explained. Each member 2 comprises a pair of bars 24 spaced apart and connected by spaced bars 25 and 26 intermediate of the ends. The bar 26 is slotted at its free lower end as at 27 to receive one of the supporting lugs or brackets 28 of the 100 radiator bottom tank 4'. The slotted end of bar 26 fits against the inner end of block 18' and is supported in part thereby when

the loaded crate is set upright on the end 6, as will be clear from Fig. 4.

The centering plate 3 fits snugly between the upper bars 24 of the side fillers 2 and 5 against the end of plate 21 when the latter is closed. It is in the form of a board with split preventing cross cleats 30 at its ends on the outer side. Said plate 3 has a central aperture 31 to receive the distance rod 10 boss 33 on the back side of the top tank 4" of the radiator 4.

When the radiator is in place and the crate is fastened shut the upper tank 4" is clamped between the crate bottom 19 and plate 3, 15 the latter serving also to prevent side movement. Endwise movement is prevented mainly by the side bars 26 in which the brackets 28 are set. Side movement of the bottom tank is prevented by the corner 20 blocks 18' which also help support the bars 26 when the crate is stood on its end 6. The tank 4' is held against the bottom 19 by means of the bars 26, the downwardly 25 facing slots 17 of which prevent the bracket 28 from moving toward cover 8.

The method of constructing the crate is to first cut the elementary strips of material to the right length and shape, and then assemble the same to form the three 30 main parts 1, 2 and 3, nails or similar means being used for fastenings. The part 1 is formed by inserting hinge pivots at the ends of the members 5 and 7, after having nailed the parts 5, 6, 7 and 8 together respectively, and then attaching the four binding wires 9, the ends being left long enough to provide tie-ends 10, as shown in Fig. 1.

In order to apply the crate to a radiator, the crate member 1 is unfolded to the position shown in Fig. 2, whereupon the radiator is laid face down against the bottom 40 of the crate. The side fillers 2 are then set in place on each side of the radiator, after which the centering plate 3 is applied. For 45 the sake of clearness in showing the ultimate position of the members 2 and 3, relative to the radiator, they are represented in said Fig. 2 as applied to the radiator before the latter is set in place, though in 50 practice they are applied after the radiator has been seated in the member 1. After the radiator and members 2 and 3 are in place the lid 8 is closed down against the

member 6, whereupon the wires are pulled tightly and twisted together at their free 55 ends, as at 35 on Fig. 3, thereby locking the parts all together in a rigid and secure position ready for shipment or storage. In closing the lid 8 care is taken that the free end tongue 14 fits in the corner groove 60 15. A locking pin 15' is preferably inserted at both corners.

To release the radiator the operation is reversed, the wires 9 being untwisted, the cover 8 swung back, and the members 3 65 and 2 being removed, leaving the radiator free to be shifted out of the member 1 ready for installation on a motor car.

By this improvement, it will be seen, I have provided for three point support or 70 suspension substantially as when the radiator is mounted on a car, and by the same means, namely the resilient bottom supporting side brackets and the distance rod boss at the top where the radiator tank is 75 reinforced to support this boss.

Although but one specific embodiment of this invention has been herein shown and described, it will be understood that numerous details of the construction shown may be altered or omitted without departing from the spirit of this invention as defined by the following claims.

I claim:

1. A foldable crate for radiators comprising a wrapper, a pair of separately formed side fillers and a top centering member, said wrapper being adapted to form four sides of a rectangular crate when folded together, said side fillers being adapted to 80 constitute two sides of the crate when set in place and said centering member being formed and adapted to engage the distance rod boss on the radiator.

2. A crate to rigidly support a radiator 95 from the three reinforced points thereof, namely the distance rod boss on the top tank and the side brackets or supporting means on the bottom tank, said crate having bottom corner pockets to receive said 100 brackets and a top middle aperture to receive the distance rod boss.

Signed at Chicago this 14 day of August, 1925.

FRED M. YOUNG.
